KEEPER MECHANISM

Joseph J. Steffan, St. Louis, Mo.; Julius A. Steffan and Dolores H. Williams, coexecutors of Joseph J. Steffan, deceased

Application September 22, 1950, Serial No. 186,171

3 Claims. (Cl. 292—341.18)

1

This invention relates to attachments for metallic door jambs provided with door stops, and more particularly to an attachment including a keeper or striking plate adapted to receive the bolt or latch of a door.

One of the objects of the invention is to produce a novel device of this kind adapted to locate a closed door in contact with the door stop of the jamb, thereby tightly closing the door and preventing the usual rattling due to varying air pressures on loosely closed doors.

Another object is to produce a hollow metallic door jamb having a keeper or striking plate adjustably secured by means of nut and bolt devices including nut members slidably interlocked with the hollow jamb to receive the bolts, so that said interlocked nut members can be readily positioned and held within the jamb before the bolts are applied to the jamb. This eliminates the perplexing problem of holding the nuts inside of the jamb during the original installation of the device, and positively prevents the nuts from falling into the hollow jamb when the bolts are deliberately removed to detach the keeper plate, or when the bolts are accidentally released from the nuts in adjusting the keeper plate.

A further object is to produce a device of this kind including a latch-receiving box located between the slidably interlocked nut members under specific conditions wherein said box serves as means for preventing release or undesirable displacement of said slidable nut members.

With the foregoing and other objects in view, the invention comprises the novel combination and arrangement of details herein shown and described to illustrate the invention. However, it is to be understood that the invention extends to variations and modifications within the scope of the claims hereunto appended.

Fig. 1 is a face view of a portion of a metallic door jamb equipped with my attachment.

Fig. 2 is a view similar to Fig. 1 with the keeper plate removed, side margins of the jamb being broken away.

Fig. 3 is a section on the line 3—3 in Fig. 1 with a portion of the door shown by dotted lines.

Fig. 4 is an enlarged vertical section on the line 4—4 in Fig. 1.

Figures 5, 6 and 7 are detail views of one of the nut members.

Fig. 8 is a detail view of a latch-receiving box.

To illustrate one form of the invention, I have shown a portion of a door jamb made of thin sheet metal having attaching flanges 10 secured to a rigid wall member 11, as shown in Fig. 3.

2

This jamb is provided with an extended door stop 12 and a latch-receiving opening 13 adjacent to said stop.

The keeper, or striking member, herein shown 5 comprises a plate 14 located in a depression 15 formed in the metallic jamb, said keeper having a latch-receiving opening 16 smaller than the corresponding opening 13 in the jamb. The keeper plate 14 is provided with round countersunk holes conforming to the heads of bolts 17, said bolts being extended through relatively large holes 18 formed in the metallic jamb at points above and below the latch-receiving opening 13 of the jamb. I will now refer to a pair of 10 suitable nut members adapted to receive threaded portions of the bolts 17.

The nut members herein shown are slidably interlocked with top and bottom walls 19 and 20 defining the upper and lower edges of the 20 latch-receiving opening 13 in the sheet metal jamb. As shown most clearly in Figures 4 and 6, the nuts are formed by U-shaped springs made of sheet metal, comprising inner and outer arms 21 and 22 embracing and slidably secured to said 25 top and bottom walls 19 and 20. The inner arm 21 of each of these thin, sheet metal nut members (Figures 4 to 7) extends beyond the outer arm 22 and may be provided with oppositely disposed inclined flanges 23 separated from each other and having concave edges (Fig. 7) facing each other to form a screw thread for the nut. However, the scope of the invention is not limited to this type of screw threads.

When the device is assembled, the screw 30 threads formed by flanges 23 lie within the hollow jamb and register with the enlarged openings 18. The countersunk head of each bolt 17 is neatly seated in a corresponding hole in the keeper plate 14 (Fig. 4), while the threaded portion of the bolt extends through a relatively large hole 18 in the jamb to engage the thread elements 23 of the nut. The nut members are slidably interlocked with the jamb and movable toward and away from the door stop 12 to provide 35 for corresponding adjustments of the keeper plate 14. During such adjustments, the bolts 17 are loosened and moved laterally in the large holes 18, said bolts being shifted with the keeper plate and nut members. Fig. 3 shows how a 40 properly adjusted keeper plate 14 cooperates with a latch 24 to locate a closed door in contact with the door stop 12.

The U-shaped nut members have return bends 26 which embrace and contact with edges of the 45 wall members 19 and 20 to properly locate the 50

threads of the slideable nuts in alinement with the enlarged bolt-receiving holes 18. A latch-receiving box 27 is provided with open flanges 28 (Figures 2, 4 and 8) clamped between the keeper 14 and portions of the metallic jamb, while the outer margin of the box lies in the latch-receiving opening 13. Said box 27 is thus interposed between the slideable nut members. It contacts with the return bends 26 of the nut members, so as to positively locate the nut threads in approximate alinement with the large bolt holes 18 and prevent undesirable displacement of the slideable nut members when said nut members are shifted with the keeper 14 and its attaching bolts 17.

These slideable nut members can be readily positioned and held within the jamb before the bolts 17 are applied to the jamb, thereby preventing the nuts from falling into the hollow jamb while the device is being assembled, or when the bolts are deliberately removed to detach the keeper plate, and also when said bolts are accidentally removed in adjusting the keeper. Furthermore, the slideable nut members are interlocked with the top and bottom walls defining the upper and lower edges of the latch-receiving opening in such a manner that the nut threads are almost automatically positioned to receive the bolts. The latch box 27 is interposed between the nut members so as to definitely locate the nuts in desirable initial positions, and thereafter positively retain the nut members in interlocking engagement with the jamb, while allowing said nut members to freely slide with the adjustable keeper.

I claim:

1. A keeper mechanism adapted for use on a hollow sheet metal door jamb having a latch-receiving opening and bolt-receiving openings above and below said latch-receiving opening, said keeper mechanism comprising U-shaped nut members having inner and outer arms slidably embracing walls of the jamb defining the upper and lower edges of said latch-receiving opening, the inner arm of each nut member having screw thread-engaging means positioned to register

with one of said bolt-receiving openings in the jamb, a keeper plate overlying the outer arms of said nut members, and bolts passing through said keeper plate and through the bolt-receiving openings in the jamb and screwed into the screw thread-engaging means of the inner arms of said nut members to secure the keeper plate to the jamb, the bolt-receiving openings in the jamb being large with respect to the diameter of the bolts extending therethrough whereby lateral adjustment of the keeper plate is permitted.

2. A keeper mechanism adapted for use on a hollow sheet metal door jamb having a latch-receiving opening and bolt-receiving openings above and below said latch-receiving opening, said keeper mechanism comprising U-shaped nut members having inner and outer arms slidably embracing walls of the jamb defining the upper and lower edges of said latch-receiving opening, a keeper plate overlying the outer arms of said nut members, bolts passing through said keeper plate and through the bolt-receiving openings in the jamb and screwed into the inner arms of said nut members to secure the keeper plate to the jamb, and a latch-receiving box positioned within the latch-receiving opening of said jamb between the U-shaped nut members and proportioned to retain said nut members in embracing engagement with the jamb.

3. The keeper mechanism of claim 2, wherein the latch-receiving box is provided with frame-like flanges lying between the keeper plate and the jamb, and loosely embracing the outer arms of the nut members.
